UNITED STATES PATENT OFFICE.

JAMES H. RAND, OF NEWTON, MASSACHUSETTS.

ADJUSTABLE INDEX.

1,025,997.

Specification of Letters Patent. Patented May 14, 1912.

Application filed January 16, 1911. Serial No. 602,852.

To all whom it may concern:

Be it known that I, JAMES H. RAND, a citizen of the United States, and resident of Newton, in the county of Middlesex and 5 State of Massachusetts, have invented new and useful Improvements in Adjustable Indexes, of which the following is a specification.

This invention relates to adjustable indexes or indicators, of the general character 10 illustrated in Letters Patent No. 890,925, issued to me June 16, 1908, to which reference is hereby made.

It has been found in practice that by reason of the handling and manipulation of the index strips, incident to repeated removals, replacements and adjustments of the strips in a constantly changing indicator, the strips, which are usually of cardboard, 15 quickly become soiled, broken, or otherwise disfigured or injured, necessitating their being replaced by new strips. To overcome this I have devised transparent protective sheaths for the index strips, said sheaths so 20 constructed as to be adjustably and interchangeably mounted in the frame of the indicator and to hold each a removable index strip, which is wholly protected from wear 25 or injury by the sheath, and which may be removed and discarded when its usefulness 30 is gone, and be replaced by another strip. Furthermore, it is possible to use in combination with such sheaths, index strips of thin, flexible paper or other material suit- 35

able for being written upon, but not having enough stiffness in itself to constitute the adjustable and interchangeable index tablet. An ordinary sheet of paper may be used for writing the inscription, and the paper then 40 cut into strips of the desired size, thus greatly reducing the cost of material and the trouble of writing the inscriptions. It has also been necessary heretofore, as shown in my Letters Patent aforesaid, to provide 45

the flanged frame for supporting the indicator strips with a spring-pressed follower, bearing against the ends of the strips, to admit of the insertion and removal of the strips without shortening them by bending 50 or buckling them for that purpose, otherwise the cardboard of which the strips were made would either be broken or cracked, or would remain permanently bent and so prevent the strips from lying flat and smooth 55 in the index frame, since cardboard which is thick enough and stiff enough to serve

for the tablets or strips without any reinforcement, is not sufficiently resilient to return again to a perfectly flat condition after it has been bent sufficiently to spring its 60 ends out of the guide channels.

With my present invention the spring pressed follower of the frame may be dispensed with, and the construction of the frame thereby much simplified, as my protective sheaths possess such resiliency that they may be inserted in and removed from the frame by bending or buckling, after which they will again resume a perfectly flat condition, and also possess sufficient 70 stiffness to serve as interchangeable tablets without breaking or crumpling as does unprotected paper under the ordinary conditions of use, while the paper indicator strips which are slipped into the sheaths may be 75 as thin and light as desired since all the requisite stiffness is furnished by the sheaths.

Still further features of my invention consist in providing each protective sheath with a longitudinal slot on its rear side, through 80 which a suitable pointed implement, or even the finger or finger nail of the user, may be inserted to push the removable index strip out of the sheath; and in so flattening the juxtaposed edge surfaces of the sheaths 85 that they will not tend to overlap, one upon another, when pressed together, but will lie edge to edge in a substantially continuous plane.

In the accompanying drawings which 90 illustrate one embodiment of my invention, Figure 1 is a face view of a portion of an adjustable indicator embodying my invention, parts being broken away; Fig. 2 is a sectional view on line 2-2 of Fig. 1; Fig. 3 95 is a sectional view, enlarged, on line 3-3 of Fig. 1; and Fig. 4 is a perspective view of one of the protective sheaths and removable index strips, showing the rear side thereof and the manner of removing the strip. 100

The supporting frame, as herein shown, consists of a body or back of suitable material such as tin or other sheet metal, *a*, having its opposite edges bent to form inwardly extending guide flanges *a'*, *a'*, providing channels for the ends of the sheaths hereinafter described.

The index strips *b* are made of paper or other thin, flat material suitable for receiving the inscription, and instead of being 110 mounted directly in the frame with their ends supported by the guide-flanges as in

my said former patent, are each slipped within and held by a protective sheath.

The protective sheath is made of stiff, transparent, resilient material such as celluloid, formed with a long, relatively narrow and flat front face or body portion *c*, through which the inscription on the index strip may be observed. The long edges of the sheath-body are turned inwardly toward each other to form guiding and retaining lips *c'*, for guiding and holding the index strips *b*. The lips *c'* are folded over on two parallel lines so as to make two rectangular folds *c''*, thereby providing a flattened edge surface *c'''* to abut squarely against a similar edge surface of the next adjacent sheath, thus avoiding any tendency of the edges of the sheaths when crowded toward each other to slip past one another, and overlap and jam, as might result if the abutting edges were simply rounded instead of flat.

The edges of the lips *c'* are spaced apart to form a slot *c''* lengthwise of the sheath, through which slot a pointed implement, such as a knife blade *K* may be inserted to push the index strip *b* lengthwise out of the sheath. Fig. 4 shows the index strip partially removed. The strips *b* might of course be made to fit sufficiently loosely in the sheaths to drop out through the open end when the sheaths are held in vertical position, but it is desirable that the strips should have a reasonably close fit in the sheaths, and in that event it is necessary to provide a slot *c''* to facilitate their removal.

The sheet celluloid sheaths, constructed as above described, are flexible, so that they may be sprung or buckled into the shape shown in dotted lines in Fig. 2, for insertion into or removal from the frame, and are also exceedingly resilient so that after

being so bent they will again resume their original, perfectly flat condition, without injury or distortion. Thus I am enabled to use two similar narrow guide-flanges *a'*, and to dispense with the spring-pressed follower shown in my said former patent.

From the foregoing it will be seen that the sheaths, which have to endure substantially all of the handling, may be practically as durable as the frame itself, will not become soiled nor worn, and will preferably protect the strips from being damaged or disfigured. Furthermore, the strips may readily be removed and replaced, and as they require no stiffness themselves, that being supplied by the sheaths, they may be made of ordinary paper whenever required by the user, thus saving the expense of procuring and printing specially manufactured card strips as has heretofore been the practice.

I claim:

An indicator device comprising a frame provided with inwardly facing guide channels, and a plurality of longitudinally resilient protective sheaths, each formed of stiff, transparent, resilient material, and having a relatively long and narrow, closed front face, and inwardly-turned retaining lips on the rear side to form a slide for removably holding indicator strips, said sheaths by their resiliency being removable from the guide channels of the frame, and interchangeably held at their ends by said guide channels.

Signed by me at Boston, Massachusetts, this seventh day of January, 1911.

JAMES H. RAND.
